MORTARLESS BRICKWORK

Josef Berlek, Radenthain, Austria, assignor to
 Oesterreichisch Amerikanische Magnesit Aktiengesellschaft, Radenthain, Austria, a joint-stock company

Application December 12, 1936, Serial No. 115,606
 In Austria March 11, 1936

5 Claims. (Cl. 266—43)

This invention relates to mortarless brickwork, especially to mortarless brickwork built up of refractory bricks with elements made from sheet metal inserted in the joints between the bricks, and in particular to refractory furnace linings, arches, partition walls or the like consisting of the brickwork specified which is not free to expand.

When refractory bricks are laid to form masonry which is not free to expand, as is the case for example when a rigid or non-yielding sheet metal jacket does not leave sufficient play for the expansion of the refractory furnace lining enclosed thereby, that is to say more particularly in the case of revolving cylindrical kilns or rotary furnaces, expansion joints must be provided to prevent the ends of the bricks from becoming crushed by the expansion pressure set up by the heating-up of the furnace. For this purpose it has been proposed to lay between the bricks strips of pasteboard of suitable thickness which keep the bricks suitably spaced during the work of laying the same, and which afterwards burn away when the furnace is heated. It has also proved useful, in laying magnesite bricks, to make provision for expansion due to heat by inserting in the main joints, sheet iron which becomes plastic and finally melts when the furnace is heated-up. In this manner account is also taken of the fact that magnesite bricks must be laid as far as possible dry, for which reason it is the general practice either to lay them without any binder with crepitating joints, or to use as binder or bedding material special anhydrous mortar (for example tar oil or linseed oil mortar) or even merely dry pulverized magnesite. If sheet metal is employed in building up brickwork of this description a cementing together of the bricks at the butt joints is also achieved simultaneously.

An object of the present invention is to prevent the occurrence of stresses during the heating-up of brickwork which is not free to expand, that is to say more particularly in the refractory linings of revolving cylindrical kilns or rotary furnaces, but also in arches and partition walls or the like, use being made, for this purpose, of elements made from metallic sheet material for insertion in the joints of brickwork, which material is of the nature of sheet iron, such elements as are used in the building up of dry magnesite brickwork. In accordance with the present invention, however, there are employed for this purpose sheet metal elements of special cross-sectional shape. The present method is applicable in all cases in which molten metal does not

come in direct contact with the refractory lining. The nature of the metal used is determined by the condition that it either will not combine with the refractory material at high temperature or at least will not have any deleterious effect upon this material and particularly on the refractory nature of this material. Iron is the preferred material in the case of the method according to the present invention also, if only on account of its low price.

Elements made from metallic material for insertion in the joints of brickwork have in general the disadvantage that their softening under heat progresses slower than the expanding of the bricks, with the result that with elements which are initially flat stresses are set up after all in the brickwork at the commencement of heating up, which are capable of loosening the brickwork structure. In order to obviate this drawback the bricks are spaced, in accordance with the present invention, to the extent required to allow for expansion due to heat, by means of sheet metal strips the spacing capacity of which is increased by virtue of the fact that they become flattened out under pressure before the metal melts. To this end there are employed sheet metal spacing elements having projections formed from the material of these elements either mechanically, for example by bending or stamping, or by hand, for example by hammering. The projections may be formed in a great variety of ways and this term is used in this description and the accompanying claims in its broadest sense. For example, there may be provided uniformly distributed protuberances or bulges, or projecting tongues obtained by bending up stamped out flaps of the metal sheet material. It has been found best to use corrugated sheet material in which the crests of the corrugations on both sides are flat.

This method of building up brickwork from refractory bricks without the use of mortar has the great advantage that the sheet metal spacing elements yield to the expansion of the bricks. Moreover, on account of the shape given to the spacing element, their thickness (including the heights of the corrugations, protuberances, bulges, etc.) may be such as to correspond to the total maximum expansion of the brick for the temperature concerned, and that not only without using more material but actually achieving a saving of material. For example, if a rotary cement kiln is to be lined with magnesite bricks having a thickness of 65 mm. at their inner ends, the working temperature is 1500° C., at which temperature the expansion of the magnesite brick

amounts to 2%. Consequently a spacing of $65 \times 0.02 = 1.3$ mm. is required to enable each brick to expand unchecked when the kiln is being heated up to this temperature. In accordance with the present invention there are used for this purpose, instead of 1.3 mm. massive sheets, material of 0.5 mm. thickness brought up to a thickness of 1.3 mm. in the manner described, for example by corrugation. These two advantages are accompanied, in the case of magnesite bricks or bricks containing magnesia (for example chromite-magnesite bricks), when spacing elements made from sheet iron are used, by the additional advantage that at the commencement of heating up, owing to abundant scale formation, there become formed considerable quantities of iron oxide which combines with the magnesia to produce magnesium ferrite, with the result that an excellent refractory cement is formed which unites the bricks to a monolithic unit.

The invention will now be described with reference to the accompanying drawing, in which Figs. 1 and 2 show a form of construction of the sheet metal element to be used in accordance with the invention, in end view and in plan view, respectively. Fig. 3 shows a modified form of construction of a sheet metal element in end view, and Fig. 4 a portion thereof in plan view; Figs. 5 and 6 show a part of the lining of a rotary cylindrical furnace erected in accordance with the invention, in elevation and in cross-section, respectively.

Referring to Figs. 1 and 2 of the drawing the sheet metal element 1 for insertion in the joints of the bricks is in profile of corrugated substantially U-shape with flat crests or waves 2 on both sides, the height of which amounting to about one-and-a-half times the thickness of the sheet metal from which it is made. The sheet metal is made in sizes approximately equal to that of the surfaces of the brick but the sizes may also be a multiple thereof, as shown in the horizontal pieces in Fig. 5. The corrugated sheet metal is of such a strength that the corrugations flatten out under a pressure smaller than that endured by the bricks or smaller than the resistance to pressure of the bricks.

The projections of the sheet metal elements may also be in the form of protuberances or bulges 3 as shown in Figs. 3 and 4, which are pressed up and pressed down in the sheet metal, and preferably projecting alternatively from both sides of the sheet metal.

In the appended claims, the term "corrugated sheet metal" is used to include sheet metal having longitudinal corrugations as well as sheet metal having struck up portions, as described herein and as illustrated by way of example in the appended drawing.

The sheet metal elements are inserted in the longitudinal and circumferential joints in the lining which is built up of the refractory bricks 4, as shown in Figs. 5 and 6 and which is encased by a rigid sheet metal jacket or shell 5.

When the furnace is being heated up the bricks expand and compress the sheet metal spacing elements inserted between them, so that the projections on these elements are pressed flat. The forces set up thereby are relatively slight and can be taken up by the bricks without danger to the structure. As the temperature increases still further the spacing elements become soft and offer no appreciable resistance to the expansion of the bricks. Finally, the iron melts and is partly squeezed out of the joints, and partly taken up

(mainly as magnesium ferrite) by the pores of the bricks. It will be understood that at temperatures approaching the melting point of the iron, the iron becomes oxidized and it is the iron oxide that combines with magnesia to form the magnesium ferrite, formed in situ in the adjacent surface portions of the bricks.

According to the provisions of the patent statutes, I have explained the principle and construction of my invention and have illustrated and described what I now consider to represent its best embodiment. However, I desire to have it understood that, within the scope of the appended claims, the invention may be practised otherwise than as specifically illustrated and described.

I claim:—

1. Method of building up refractory masonry, which comprises laying up refractory bricks without mortar, leaving spaces between the said bricks sufficient to allow for expansion of the bricks during a heating up step, and only partly filling the joints by the insertion of corrugated sheet metal, the metal of said sheet being oxidizable at high temperatures, and said metal and its oxide being free from deleterious action on the refractory quality of said bricks, and which sheet metal elements are adapted to flatten out under the pressure of the expanding bricks, and heating up the thus built up brickwork, for causing expansion of the bricks and thereby at least partly flattening out the corrugated sheets, and thereafter further heating such assemblage sufficiently to soften the metal of said sheets, and allowing oxidation of said softened metal to occur.

2. Method of building up a refractory brick lining in a rotary furnace, which comprises laying refractory magnesia-containing bricks, without mortar, as a lining in a rotary furnace, while leaving sufficient spaces between the bricks to allow for expansion of the bricks during the step of heating up the furnace to a temperature at which iron softens, and partly filling the joints between the bricks by the insertion therein of corrugated sheet iron spacing pieces, adapted to flatten out under the pressure of the expanding bricks, and heating the furnace structure thus built up, whereby firstly the expansion of the bricks, due to the heating, causes the sheet iron spacing elements to become somewhat flattened out, after which, upon heating to higher temperatures, the iron becomes softened and in part oxidized and iron oxide so formed reacts with magnesia of the bricks to form magnesium ferrite which can act as a cementing agent for cementing adjacent bricks together.

3. Method of building up a refractory brick lining in a rotary furnace, which comprises laying refractory magnesia-containing bricks, without mortar, as a lining in a metal walled metallurgical furnace, while leaving sufficient spaces between the bricks to allow for expansion of the bricks during the step of heating up the furnace to a temperature at which iron softens, and partly filling the joints between the bricks by the insertion therein of corrugated sheet iron spacing pieces, adapted to flatten out under the pressure of the expanding bricks, and heating the furnace structure thus built up, whereby firstly the expansion of the bricks, due to the heating, causes the sheet iron spacing elements to become somewhat flattened out, after which, upon heating to higher temperatures, the iron becomes softened and in part oxidized and iron oxide so formed is, to some extent at least, absorbed by the surface

portions of said bricks and reacts with magnesia of the bricks to form magnesium ferrite, which is refractory.

4. Furnace masonry which comprises refractory bricks laid with open spaces left between adjacent bricks sufficient to permit expansion of the said bricks by heating, corrugated sheet metal inserts only partly filling said spaces, said corrugated sheet metal inserts being adapted to be flattened out by the expansion of said bricks during the step of heating up of said bricks and be-

fore the said metal insets substantially soften due to high heat, such assemblage being capable of further heating sufficiently to soften and oxidize the metal insets, whereby the metal oxide can be, in part at least, taken up by the refractory bricks without substantial injury to the refractory qualities of such bricks.

5. A structure as in claim 4, in which the corrugations of said corrugated sheet metal spacing elements have substantially flat tops.
